UNITED STATES PATENT OFFICE.

GEORGE P. CARROLL, OF BRIDGEPORT, CONNECTICUT.

VALVE AND CONNECTION.

No. 924,964.

Specification of Letters Patent.

Patented June 15, 1909.

Original application filed March 1, 1907, Serial No. 360,055. Divided and this application filed June 5, 1907.
Serial No. 377,349.

To all whom it may concern:

Be it known that I, GEORGE P. CARROLL, a citizen of the United States, residing at Bridgeport, in the county of Fairfield and State of Connecticut, have invented a new and useful Valve and Connection, of which the following is a specification.

This application is a division of my application Ser. No. 360,055, filed March 1, 1907, 10 entitled electric expansion valve, in which the claims were based on the construction and immediate operation of the valve. In this application my invention relates to valves automatically opened when power is 15 simultaneously applied to produce some other result and automatically closed when the application of power to such other purposes is terminated; and it especially relates to expansion valves and other valves in refrigerating systems which are made to open 20 and close simultaneously with the starting and stopping of the system. The means employed are automatic means whereby at the time the power is applied to produce some other result, such as the operation of a refrigerating system, whether of the compression or absorption type, the valve, by the application of electric power, is opened; and whereby, at the time such application of 25 power is terminated, the valve is similarly closed. The means also consist of automatic means whereby, while refrigerating system or other object to which the main power was applied is being operated, the valve is locked 30 in an open position so that it will remain open without the further employment of power until the main application of power has terminated.

In the drawings Figure 1 is a front elevation of the valve and connections, the latter being diagrammatic in part. Fig. 2 is a side elevation of a switch and connections. Fig. 3 is a vertical section of the valve.

Electric mains 1 lead to and return from a 45 motor M operatively connected with a compressor K of a refrigerating system. Obviously such mains could be made to lead to and return from an electric heater used to heat the still of an absorption refrigerating 50 system and the combination of elements would generically be the same.

A switch 2 is used to turn on the current to the motor, or other object to which the current is to be applied, by making contact at 3;

and, as a part of the movement of closing or 55 breaking the current, intermediately to make contact at 4 so as to send a current through a branch line 5 provided with a resistance 6. Another branch line 7 is provided with a resistance 8. 60

A valve casing 9 has an inlet port 10 adapted for connection with a high pressure pipe H and an outlet port 11 adapted for connection with an expansion coil C. Intermediate between the inlet and outlet is a horizontal conical valve seat 12. A needle valve 13 is adapted to occupy and close the valve seat from above and when not otherwise raised is pressed down upon its seat by a coiled spring 14, abutting at one end against 70 the inside of the top cap 15 of the casing and at its other end against the top of the needle valve. The needle valve is guided along its length by the guides 16 and 17, cast as parts of the casing, so that the valve readily finds 75 its seat. The upper part of the valve is provided with a projecting pin 18, adapted for engagement with the slotted end 19 of the inner lever 20, extending in a horizontal direction. The other end of this lever is secured to or made of one piece with a lever shaft 21, journaled at one end in the back wall of the casing and passing out through the front of the casing where it is provided with a suitable stuffing box 22. Instead of 80 the pin 18 the top of the valve might be provided with a stationary collar and instead of the slot 19 the inner lever might be provided with a fork to engage the collar on its underside. An outer lever 23 is secured to the 85 outer end of the lever shaft 21 and extends in a horizontal direction opposite to that of the inner lever.

Pivoted at 24 on the extended outside part of the casing 9 is a three-part lever 95 25 having its main arm 26 extending horizontally toward and terminating in a position just above the outer end of the outer lever 23. The extreme end of the main arm 26 is provided with an adjusting screw 27 so 100 that the contact of the main arm 26 and the outer end of the outer lever may be suitably regulated. The length with which the screw projects below the main arm determines the depression of the outer lever 23 and the consequent elevation of the inner lever 20, the pin 18, and the needle valve 13 from off its seat. Substantially at right angles to the

main arm an upper arm 28 extends upward and a lower arm 29 extends downward from the pivot 24.

Intermediately placed in the branch line 7 is an electro-magnet 30. This magnet is placed immediately under the main arm 26, which is there provided with an armature on its under side, and when energized by the passage of a current depresses the main arm 26 downward so as to be in contact through the adjusting screw 27 with the outer end of the outer lever 23. The depression of the main arm 26 overcomes a spring 31 which keeps the main arm elevated when the magnet is not energized or when the main arm is not locked in a depressed position. The depression of the main arm 26 throws the upper arm 28 to the left and the lower arm 29 to the right.

20 A dog 32, provided with an armature on its upper side, pivoted at 33 on the extended outside part of the casing 9, has a tooth 34, which rests upon the inclined outside of the extreme top of the upper arm 28 while the main arm 26 is elevated. But with the depression of the main arm by the energizing of the electro-magnet 30, the upper arm 28 slips inside of the tooth 34 and there continues in a locked position after the electro-magnet 30 is no longer energized. If necessary a light spring may be provided to press the dog 32 downward so as to be constantly ready to permit of the upper arm being engaged; or, as shown, the force of gravity may be sufficient to depress the dog.

40 A switch 35 is pivoted at 36 on the extended outside part of the casing 9 and connects the electro-magnet 30 back to the mains 1. This switch has two limit arms 37 and 38 and also a weight arm intermediate between them and ending in a small globular weight 39. Both these limit arms are adapted in turn to be engaged by the lower end of the lower arm 29 as it is moved to the right 45 by the depression of the main arm 26 and back again by its elevation. When the electro-magnet 30 is energized, the first effect of depressing the main arm 26 is to lock the upper arm 28 into engagement with the tooth 34. Simultaneously the lower arm 29 is thrown against the limit arm 37 so as to thrust it to the right and to throw the center of gravity of the weight 39 to the right of the center of the pivot 36. This 55 shifting of the weight 39 then opens the switch and breaks the flow of current through the branch line 7. The time required for this last action is sufficient to permit the upper arm 28 to become engaged 60 with the tooth 34 before the current is broken.

65 A second electro-magnet 40 is secured to the upper part of the extended outside part of the casing 9 immediately above the dog 32 and intermediate in the branch line 5. When

the electro-magnet 40 is thus energized it lifts the dog 32 and thereby releases the upper arm 28. This action permits the spring 31 to raise the main arm 26, the electro-magnet 30 being, as just seen, in a 70 condition of non-energization. The lifting of the main arm 26 throws the lower arm 29 against the limit arm 38 so as to thrust it to the left and to throw the center of gravity of the weight 39 to the left of the center 75 of the pivot 36. This shifting of the weight then closes the switch 35 and makes possible a flow of current to again energize the electro-magnet 30.

The method of operation is as follows: 80 When the valve is used, as especially intended, as the expansion valve in a refrigerating system, the turning on of the electric current to the system, by the switch 2 making contact at 3, also supplies a current to 85 the branch line 7. The electro-magnet 30 is thereby energized since the switch 35 has been closed by the prior shifting of the weight 39 to the left. The energizing of the electro-magnet 30 depresses the main 90 arm 26 and the outer lever 23. This action raises the inner lever 20 and the pin 18 so as to lift the needle valve 13 from off its seat 12. Simultaneously with the depression of the main arm 26 the upper arm 28 is locked in 95 engagement with the tooth 34 and the shifting of the weight 39 to the right next opens the switch 35 and breaks the flow of current through the branch line 7. When subsequently the current is turned off so as to 100 shut down the system, for an instant, by the switch 2 making an intermediate contact at 4, a current is sent over the branch line 5 to the electro-magnet 40. The energization of this electro-magnet lifts the dog 32, disengages the upper arm 28, permits the main arm 26 to rise and again closes the switch 35. As the main arm 26 rises, the spring 14 depresses the valve 13 into its seat and forces 105 down the inner lever 20 so as to elevate the outer lever 23 into its original position. It is to be observed that while the turning on of the current also energizes the electro-magnet 40, this has no effect other than to raise the dog 32 for an instant at a time when it is 110 not in engagement.

The flow of fluid through the expansion valve is thus made automatically to begin with the starting of the system and to end with its shutting down. The electric current opens the valve and is then shut off, with the locking of the valve in an open position, not to be turned on again until the valve is to be closed. By thus locking the valve no current is wasted in maintaining the 115 valve in an open position. Owing to greatness of the pressure on the high side of the usual ammonia system, being oftentimes normally 180 lbs., a needle valve such as 13 must be employed as the expansion valve, 120 125 130

rather than some form of gate valve or rotary valve exposing greater surface to the high pressure. And owing to the extreme tenuity of ammonia gas, the part of the mechanism, 5 like the shaft 21 connecting the valve with moving parts outside of the casing, may have a rotary rather than a reciprocating motion.

When the valve is used as the expansion valve of a refrigerating system, it is to be understood that a pressure regulating valve may be placed in the expansion coil C. Such a valve is shown and described in my application Ser. No. 351,068, filed Jan. 7, 1907, entitled automatic expansion valve. While 10 the valve shown and described is an expansion valve, the same principle of opening and closing in connection with the turning on and off of power used for other purposes would apply to a single stage condenser valve, such 15 as is described in the latter part of the description in my application Ser. No. 364,418, filed March 25, 1907, entitled electric water valve; and some of the following claims are generic to cover such a valve as well as other 20 valves. So also the principle of closing in connection with the turning off of power used for other purposes would apply to the condenser valve shown and described in my application Ser. No. 371,822, filed May 4, 1907, 25 entitled pressure and electric condenser valve; and some of the generic claims cover a combination with such a valve. It is also to be understood that in place of the motor M and the compressor K there could be substituted 30 the heater of an absorption system; and also that the power to open and close the valve could be used simultaneously to turn on and off any heating agent such as steam or gas as applied to heating the still of such absorption 35 system. Yet again the "other results" and the "other mechanism" in the claims would include the actuation of such condenser valves as are above referred to, both in a compression and in an absorption system automatically operated.

I claim:

1. In combination an apparatus for drawing in gas and making the same more dense, a valve, means for applying power simultaneously to operate said apparatus and to open said valve, automatic means operative to shut off the power so applied to open said valve, and means for subsequently shutting off the power operating said apparatus and closing said valve.

2. In combination an apparatus for drawing in gas and making the same more dense, a valve, means for applying power simultaneously to operate said apparatus and to open said valve, automatic means electrically actuated so as to shut off the power applied to open said valve, and means for subsequently shutting off the power operating said apparatus and closing said valve.

65 3. In combination an apparatus for draw-

ing in gas and making the same more dense, a valve, means for applying power simultaneously to operate said apparatus and to open said valve, automatic means operative to shut off the power so applied to open said 70 valve, and means for subsequently simultaneously shutting off the power operating said apparatus and closing said valve.

4. In combination an apparatus for drawing in gas and making the same more dense, 75 a valve, means for applying power simultaneously to operate said apparatus and to open said valve, automatic means electrically actuated so as to shut off the power applied to open said valve, and means for subsequently simultaneously shutting off the power operating said apparatus and closing said valve.

5. In combination an apparatus for drawing in gas and making the same more dense, 85 a valve, means for applying power to operate said apparatus and to open said valve, and automatic means actuated by the power applied to open said valve to shut off the power so applied.

6. In combination an apparatus for drawing in gas and making the same more dense, a valve, means for applying power to operate said apparatus and to open said valve, and automatic means actuated by electric power 95 to shut off the power applied to open said valve.

7. In combination an apparatus for drawing in gas and making the same more dense, a valve, means for applying power to operate 100 said apparatus and to open said valve, automatic means actuated by the power applied to open said valve to shut off the power so applied, and means for subsequently shutting off the power operating said apparatus 105 and closing said valve.

8. In combination an apparatus for drawing in gas and making the same more dense, a valve, means for applying power to operate said apparatus and to open said valve, automatic means actuated by electric power to 110 shut off the power applied to open said valve, and means for subsequently shutting off the power operating said apparatus and closing said valve.

9. In combination an apparatus for drawing in gas and making the same more dense, a valve, means for applying power simultaneously to operate said apparatus and to open said valve, and automatic means actuated by the power applied to open said valve to shut off the power so applied.

10. In combination an apparatus for drawing in gas and making the same more dense, 115 a valve, means for applying power simultaneously to operate said apparatus and to open said valve, and automatic means actuated by electric power to shut off the power applied to open said valve.

11. In combination an apparatus for draw-

ing in gas and making the same more dense, a valve, means for applying power simultaneously to operate said apparatus and to open said valve, automatic means actuated by the power applied to open said valve to shut off the power so applied, and means for subsequently shutting off the power operating said apparatus and closing said valve.

12. In combination an apparatus for drawing in gas and making the same more dense, a valve, means for applying power simultaneously to operate said apparatus and to open said valve, automatic means actuated by electric power to shut off the power applied to open said valve, and means for subsequently shutting off the power operating said apparatus and closing said valve.

13. In combination an apparatus for drawing in gas and making the same more dense, a valve, means for opening said valve by mechanical action or for closing it, a device for mechanically acting upon said means so as to open said valve, means for applying power to operate said apparatus and to act on said device with such effect, and means actuated by the power so acting on said device to shut off the power applied to said device.

14. In combination an apparatus for drawing in gas and making the same more dense, a valve, means for opening said valve by mechanical action or for closing it, a device for mechanically acting upon said means so as to open said valve, means for applying power to operate said apparatus and to act on said device with such effect, and means actuated by electric power to shut off the power applied to said device.

15. In combination an apparatus for drawing in gas and making the same more dense, a valve, a magnetizable device operative when magnetized to open said valve, an electric device operative when energized to

so magnetize said former device, electric connections to and from said electric device, a switch in said connections, means whereby when said device is so magnetized it also opens said switch, and means for applying

power to operate said apparatus and to send a current through said electric connections.

16. In combination an apparatus for drawing in gas and making the same more dense, a valve, a magnetizable device operative when magnetized to open said valve, an electric device operative when energized to so magnetize said former device, electric connections to and from said electric device, a switch in said connections, means whereby said device is so magnetized it also opens said switch, means for applying power to operate said apparatus and to send a current through said electric connections, and means for subsequently shutting off the power operating said apparatus and closing said valve and said switch.

17. In combination an apparatus for drawing in gas and making the same more dense, a valve, a magnetizable device operatively connected to said valve, an electric device operative when energized to act on said device so as to open said valve, electric connections to and from said device, a switch in said connections, means whereby when said device is so acted upon it also opens said switch, and means for applying power to operate said apparatus and to send a current through said electric connections.

18. In combination an apparatus for drawing in gas and making the same more dense, a valve, a magnetizable device operatively connected to said valve, an electric device operative when energized to act on said device so as to open said valve, electric connections to and from said device, a switch in said connections, means whereby when said device is so acted upon it also opens said switch, means for applying power to operate said apparatus and to send a current through said electric connections, and means for subsequently shutting off the power operating said apparatus and closing said valve and said switch.

GEORGE P. CARROLL.
